UNITED STATES PATENT OFFICE.

ERNEST H. BENNETT, OF EAST ORANGE, NEW JERSEY, ASSIGNOR TO JOHN H. BROMLEY AND EDWARD BROMLEY, OF PHILADELPHIA, PENNSYLVANIA.

DESIGN FOR A RUG.

SPECIFICATION forming part of Design No. 27,681, dated September 21, 1897.

Application filed August 13, 1897. Serial No. 648,174. Term of patent 3½ years.

To all whom it may concern:

Be it known that I, ERNEST H. BENNETT, a citizen of the United States, residing at East Orange, county of Essex, State of New Jersey, 5 have invented and produced a certain new and original Design for a Rug, of which the following is a full, clear, and exact description, reference being had to the accompanying drawing, forming a part of this specification.

10 My design is intended for the surface ornamentation of a woven rug. Its distinguishing features comprise parallel rectangular line-borders a and b and between them a series of floral ornamental figures, as indicated 15 at c. The field-center contains an irregular line-figure d, outside of which the space is filled with small figures, such as e, and the inside with a figure f, having a central diamond-shaped portion filled with connected 20 rosettes and with diamond-shaped ends.

I claim—

The design for a rug, substantially as set forth.

In testimony whereof I have hereunto affixed my signature this 12th day of July, A. D. 1897.

ERNEST H. BENNETT.
